METAL WINDOW SCREEN

Charles H. Boylan, Jr., and Peter Joseph
Sehlinger, Louisville, Ky.Substituted for abandoned application Serial No.
714,368, December 6, 1946. This application.

October 30, 1948, Serial No. 57,528

3 Claims. (Cl. 160—371)

1

This invention relates to a metal window screen for application to windows and doors, wherein the frame is formed of sheet metal in which the screen mesh is interlocked with male and female formations provided in the metal frame, this being a substitute of their abandoned application Serial No. 714,368, filed December 6, 1946.

A feature of the invention resides in the corner structure for retaining the corner abutments of the side and end frame members securely locked and reinforced.

Thus, the invention resides in forming the frame members of the screen from sheet metal strips, each of which is folded longitudinally to provide a rolled finish along the outer edge of the frame with an inwardly extending panel U-shaped in cross section to receive and embrace the edges of the screen mesh. The screen mesh is then interlocked to be firmly secured and stretched within the frame members by stamping or rolling a longitudinally extending bead, such as to form an interlocking offset by which the wire mesh is stretched and secured.

More particularly, however, the ends of each of the frame members are mounted to abut each other at the respective corners to be secured by corner gussets of sheet metal to which the members are locked against longitudinal displacement by a break in the bead formation, as hereinafter more fully set forth and described, it being understood that changes, modifications and variations in the structure as herein specifically disclosed, may be resorted to as falling within the scope of the invention as claimed.

The full nature of the invention will be understood from the accompanying drawings and the following description and claims:

Fig. 1 is a plan view showing a section of a metal screen structure, with parts broken away.

Fig. 2 is a section taken on the line 2—2 of Fig. 1.

Fig. 3 is a section taken on the line 3—3 of Fig. 1.

In the drawings there is shown a metal screen applicable for screening windows, doors and the like, which includes the wire mesh screen 10, side frame members 11, and end frame members 12. In larger screens it may be desirable to provide a cross member 13 extending between and secured to opposite side frame members 11. Each frame member 11 and end member 12 has its ends mitered as indicated at 14 for direct abutment to provide a rectangular frame of the usual character. The mitered and abutting ends of the side and end members are secured and held

2

together by the corner gusset plates 15, there being provided one such corner gusset plate 15 at each of the four corners of the usual rectangular frame. Wherein a cross plate 13 may be employed, side gusset plates 16, triangular in shape, may be employed to interlock and secure the adjoining ends of the cross member 13 to the side members 11, respectively.

The side and end members 11, 12 are formed 10 of sheet metal folded centrally and longitudinally to provide the opposed portions 17, 18 with an outer roll 19, such as to form a finishing and reinforcing outer edge. Between the portions 17, 18 the wire mesh 10 is inserted with its edge 15 lying close to the roll 19. The side and end members are thus arranged to embrace the edges of the wire mesh, but with their mitered edges 14 in abutment. In such relative position the corner gusset plates 15 are inserted to lie against one 20 side of the wire mesh, one leg being embraced by the portions 17, 18 of the side member 11 and the other leg thereof by said portions of the end member 12.

With the wire mesh 10 and the gusset plates 25 15 thus embraced by and between the side and end members, the structure is locked in place by deforming their respective adjacent surfaces through crimping, stamping, rolling and the like. As herein shown with the structure assembled, 30 the side and end members 11, 12 are formed with centrally and longitudinally formed beads 20, 21 running throughout substantially but not entirely the full length of the respective members, the bead 21 being formed in the portion 18 to nest 35 within the bead 20 formed in the portion 17. In deforming the metal to form said interlocking beads, the wire mesh and a portion of the gusset plates are similarly and correspondingly deformed to interlock therewith. Thus, said beads 40 being formed in the members to extend longitudinally thereof throughout substantially their entire length, act both as reinforcing and strengthening formations to lend rigidity to the frame members, as well as provide an interlocking 45 between the members, wire mesh and gusset plates.

However, to interlock said frame members with the gusset plates to prevent displacement thereof longitudinally of the beads 20, 21, said beads are 50 terminated short of the abutting ends of the frame members, as indicated at 22, merging into a flat or unbeaded portion indicated at 23. Thus, spaced from the beaded portions 20, 21 and separated therefrom by the normally flat portion 23, there 55 is provided a short interlocking bead portion 24,

25 adjacent to and running into the respective end members. By reason of the shoulder formation at the ends of the beads 20, 21, as indicated in Fig. 2, and the adjacent spaced shoulders formed by the beads 24, 25, as indicated at 26, an interlock with the wire mesh and gusset plates is provided against longitudinal displacement of the side and end members respectively relative thereto.

Wherein a cross member 13 may be employed the gusset 16 is interlocked, together with the wire mesh 19, against lateral or inward displacement by the interlocking beads 20, 21, and against longitudinal displacement by the interlocking beads 27 formed centrally and longitudinally of the cross member 13. The cross member 13 is, therefore, preferably formed of two strips of sheet metal lying adjacent each other on opposite sides of the wire mesh with their ends secured together between the portions 17, 18 of the side frames 11 and their intermediate portions secured together by rivets 28.

With the wire mesh extending between the opposed portions 17, 18 of the side and end members, upon forming the bead 21 therein, the wire mesh will be stretched in conforming to the bead so that any sag is removed and the mesh tightened and thereby clamped taut without the necessity or requirement of extraneous means usually necessary for this purpose.

From the above described structure it will be observed that all of the metal screen, including the frame, may be readily formed with the wire mesh firmly secured and stretched thereby within the frame members and the frame members secured at their corners by interlocking deformations developed through a mere stamping or rolling operation and without employing extraneous or other securing means. Furthermore, the deformations of the side and end members, such as to secure them together with the wire mesh, provides a reinforcing medium which also lends a decorative and finished appearance to the structure.

The invention claimed is:

1. A metal screen for windows, doors and the like comprising side and end frame members of sheet metal folded to U-shaped cross section and having mitered abutting ends, a panel of wire mesh having its side and end edges extending into and embraced by the folded portions of said members respectively, interlocking beads formed in said members and wire mesh for gripping and securing said panel therein, corner plates extend-

ing into and embraced by the folded portions of said members adjacent their corner forming ends, and interlocking elongated beads formed in the respective end portions of said members and said plates to provide opposed and spaced interlocking end shoulders, whereby relative movement of said plates and members longitudinally thereof will be prevented.

2. A metal screen for windows, doors and the like, comprising side and end frame members of sheet metal folded to U-shaped cross section and having mitered abutting ends, a panel of wire mesh having its side and end edges extending into and embraced by the folded portions of said members respectively, corner plates extending into and embraced by the folded portions of said members adjacent their corner forming ends, and a series of decorative and reinforcing beads formed longitudinally of said members for gripping and securing said panel and corner plates therein, said beads including spaced end shoulders within the area of said corner plates to prevent relative movement of said plates and members longitudinally thereof.

3. A metal screen for windows, doors and the like, comprising side and end frame members of sheet metal folded to U-shaped cross section arranged to provide a frame structure with their respective adjacent ends forming corners, a panel of wire mesh having its side and end edges extending into and embraced by the folded portions of said members respectively, corner plates extending into and embraced by the folded portions of said members at the corners of said frame structure, and a series of interlocking deformations formed in said members longitudinally thereof, said deformations being spaced from each other within the area of said corner plates for providing opposed and spaced interlocking shoulders to prevent relative movement of said plates and members longitudinally thereof and secure said panel therein.
